Attorneys.

UNITED STATES PATENT OFFICE.

DAVID PATON, OF NEW YORK, N. Y., ASSIGNOR TO JOSEPH WILD & CO., OF SAME PLACE.

DESIGN FOR A CARPET-PATTERN.

Specification forming part of Design No. 5,280, dated September 26, 1871.

To all whom it may concern:

Be it known that I, DAVID PATON, of New York, in the county and State of New York, have invented a new and original Design for a Printed Carpet, of which the following is a specification:

The nature of my design is fully represented in the accompanying colored sketch, to which reference is made.

I claim as my invention—

The design for a carpet, as shown.

DAVID PATON.
